S. TOOTILL

GRAMOPHONE TONE ARM

Filed Oct. 10, 1922

FIG. 1.

FIG. 2.

Inventor
Sidney Tootill
by Robert W. Jenner
Attorney.

UNITED STATES PATENT OFFICE.

SIDNEY TOOTILL, OF LONDON, ENGLAND.

GRAMOPHONE TONE ARM.

Application filed October 10, 1922. Serial No. 593,494.

To all whom it may concern:

Be it known that I, SIDNEY TOOTILL, subject of the King of Great Britain, residing at 244 Tottenham Court Road, London, 5 W. 1, in the county of London, England, have invented certain new and useful Improvements in Gramophone Tone Arms, of which the following is a specification.

This invention relates to gramophones and like talking machines of the portable type, the characteristic feature of which is to provide means for allowing the tone arm to be lowered from its working position. By lowering the said tone arm from the 15 working position, the height of the cabinet in which the instrument is placed can be reduced without impairing the tonal effect of the instrument when in operation.

The invention consists in supporting the tone arm, with its accompanying sound box and stylus in a flanged cylindrical socket, the flange of such socket being secured by screws to the motor board. The cylindrical part of such socket is provided with oppositely disposed angular and horizontal slots or grooves with which the projecting ends of a rod engage, such rod passing through the ball shaped enlarged end of the tone arm, or short studs could be used in place 30 of the said rod.

To enable this invention to be clearly understood reference is made to the drawings in which:—

Figure 1 shows a side elevation of the tone arm in its elevated or working position in the socket.

Figure 2 shows a view of the tone arm in its lower position in the socket.

In the drawings *a* designates the motor board of the machine to which is secured the mechanism (not shown) for rotating a turntable, adapted to support a disc record as is well understood. The tone arm *b* is pivotally secured at its enlarged end in a flanged socket *c* attached to the motor board *a*, the said arm having at its outer end a slotted tubular socket for securing the sound box and stylus of the usual type. The larger end 45 of the tone arm *b* is surrounded by a collar *b* of spherical contour externally form-

ing a loose fit in the flanged socket *c*. A rod *d* passes diametrically through the end *b* of said tone arm and the collar *b*, the projecting ends of which rod *d* act as trunnions and engage with the angular slots *c* and the horizontal slots *c* in the socket *c*, consequently when the tone arm is rotated in its socket *c* by hand, the tone arm *b* is raised to a higher position by reason of the ends of the rod *d* engaging with the angular slots *c* after which the projecting ends of the rod *d* engage with the horizontal slot *c* which permits the tone arm to move in a horizontal direction to follow the track or grooves on the face of the record by means of the stylus engaging said grooves thereon in the known manner.

In operation when it is desired to change a record and place a new record upon the turntable the tone arm with its sound box 70 and stylus is lifted up and moved in a horizontal direction clear of the record and turntable, a suitable soft pad being provided upon which the stylus can be deposited where it remains until the stylus is again 75 placed upon a new record and the reproduction of another record effected.

The method of carrying my invention into effect is capable of variation without departing from the construction shown and described.

What I claim is:—

In a sound reproducing machine, a horizontal supporting board, a tubular socket secured in the said board and provided with slots having horizontal upper portions and downwardly inclined lower portions, and a tone arm having its larger end portion mounted loosely in the said sleeve and provided with lateral projections which engage 85 with the said slots and enable the tone arm to be raised and lowered with relation to the said board.

In testimony whereof I have hereunto set my hand in presence of two subscribing witnesses.

SIDNEY TOOTILL.
